(57) **CLAIM**

The ornamental design for a gaming machine, as shown and described.

DESCRIPTION

FIG. 1 is a front perspective view of a gaming machine showing our new design;

FIG. 2 is a front view thereof;

FIG. 3 is a top view thereof;

FIG. 4 is a front perspective view of a second embodiment of a gaming machine showing our new design;

FIG. 5 is a front view thereof; and,

FIG. 6 is a top view thereof.

The broken lines immediately adjacent to the shaded areas define the bounds of the claimed design and form no part thereof. The oblique line shading on the input deck and the display screen shows that the surfaces are transparent, translucent, highly polished, reflective, mirrored, or shiny surfaces. The broken lines depicting the remainder of the gaming machine illustrates environmental structure and form no part of the claimed design.
